His Attorney.

UNITED STATES PATENT OFFICE

2,170,676

ELECTRIC CUT-OUT

Ralph S. Bennett, Pittsfield, Mass., assignor to
 General Electric Company, a corporation of
 New York

Application December 20, 1938, Serial No. 246,873

4 Claims. (Cl. 200—114)

The present invention relates to electric cut-outs and more particularly to fuse cutouts of the enclosed drop-out type.

- 5 In some installations of enclosed drop-out fuse cutouts, difficulties have been experienced due to the entrance into the cutout housings of insects such as wasps which build nests of mud or other material inside of the housings and thereby cause 10 electrical or mechanical failures.
- 10 It is therefore an object of the present invention to provide, in an enclosed drop-out cutout, an improved construction and arrangement of barrier means which will keep out insects but which at the same time will not interfere with 15 either the manual or the automatic operation of the cutout.

The details of that which I believe to be novel and my invention will become apparent from the following description and the claims appended 20 thereto, taken in conjunction with the accompanying drawing in which Fig. 1 shows a sectional elevation of an exemplary form of enclosed drop-out cutout embodying the improved barrier means of my present invention; Fig. 2 25 shows in perspective the fuse and door assembly of the exemplary cutout, and Fig. 3 shows a cross-section taken along the line 3—3 of Fig. 1.

As will be seen by reference to the drawing, the 30 illustrated cutout has a casing 10 of porcelain or other suitable insulating material to the rear of which is secured a mounting bar 11 for attachment of the cutout to any suitable support. The inner wall of this casing is formed with an electric creepage and gas barrier 12 upon opposite 35 sides of which are mounted terminal contacts 13 and 14. These terminal contacts 13 and 14 are provided with clamping sockets 15 and 16, respectively, for attachment of connection leads thereto. Upper contact 13 is provided with a 40 pair of resilient latching fingers 17, one of which is shown in the drawing, for engagement with the upper end of a fuse holder, and is provided also with a contact finger 18 backed by means of a spring strip 19. On the inner wall of the casing, adjacent the lower end thereof, is a hinge bracket 20.

The fuse assembly of the illustrated cutout includes a tubular expulsion fuse holder 21 carried by bosses 22 and 23 formed integrally with 50 a door 24 which is adapted to close the open front of casing 10. For support of the fuse-and-door assembly there is provided a toggle lever 25, the upper end of which is pivotally attached to door boss 23 by means of screws 26 and the 55 lower end of which lever is hingedly mounted on

bracket 20. Normally the hinged lever is held against movement relative to the fuse holder by means of a fuse link in the holder, one end of which fuse link, designated 27, is clamped to the hinged lever by suitable terminal clamping means indicated at 28. A contact arm 29, pivotally mounted on the toggle lever as indicated at 30 and biased by coil spring 31, is provided for effecting electric connection between the lower end of fuse link 27 and lower stationary contact 14 carried by the casing. A good electric connection between lever 25 and contact arm 29 is provided by a flexible metallic shunt strip 33, the opposite ends of which are connected with the lever and the contact arm by means of screws 34 and 35, respectively, or other suitable means. Connection of the upper end of fuse link 27 with upper stationary contact 13 is effected through engagement of contact finger 18 with the terminal cap 36 on the upper end of fuse holder 21. The 20 fuse assembly is latched in operative position by engagement of fingers 17 with terminal cap 36, and door 24 is provided with a handle 37 for manual operation of the fuse assembly into and out of operative position. As is well known to 25 those skilled in the art, operation of the fuse link in holder 21, when the fuse assembly is in the connected position illustrated, releases toggle lever 25 so as to permit relative movement between the lever and fuse holder. The lower end 30 of the fuse holder thereupon swings outwardly and downwardly so as to release terminal cap 36 from latching fingers 17 and permit the fuse assembly and door to swing about hinge bracket 20 to a dropped out position. 35

As will be seen from Fig. 1, casing 10 and door 24 form a compartment which is open at the lower end for discharge of gases from fuse holder 21. Heretofore the opening at the lower end of this compartment has permitted entrance into 40 the cutout casing of wasps or other insects which build nests of mud or other material in the casing. Such nests, if built between the stationary contacts 13 and 14, may cause short-circuiting or arc-over between the contacts. Also, the nests 45 may be built so as to interfere with release of the upper latch or with collapse of the toggle mechanism so as to prevent drop-out of the fuse assembly upon fuse operation. To overcome this difficulty I have provided improved 50 barrier means in the form of a relatively thin and flexible plate 40 which may be constructed of metal or insulation material and which extends transversely of the fuse compartment into proximity or contact with the inner walls of cas- 55

ing 10 and the inner face of door 24, as best shown in Fig. 3. This barrier plate is supported intermediate lower contact 14 and the lower open end of the fuse compartment so as to prevent entrance of insects into the portion of the compartment occupied by the stationary contacts, the fuse terminals and the upper pivotally attached end of lever 25. Support of the plate is effected by attachment thereof to lever 25 by means of the screw 34 which secures the lower end of shunt strip 33. The barrier plate is formed with a slot having a rectangular portion 41 extending normally to the side walls of the casing and arranged to relatively closely accommodate lever 25. Another portion of this slot, designated 42, is formed to relatively closely surround fuse holder 21. The front of the portion 42 of the slot is open, while the rear of this portion 42 is connected by means of a narrow portion 43 with the portion 41 of the slot. This construction provides for movement of the lower end of the fuse holder outwardly in slot portion 42 and relative to lever 25 when the lever is released upon fuse operation.

Thus it will be seen plate 40, while providing an effective barrier against the entrance of insects into the interior of the cutout housing, at the same time interferes in no way with collapse of the toggle mechanism upon fuse operation. This form of barrier has the additional advantages that it is light, inexpensive, and may be readily applied to common forms of drop-out cutouts employing a toggle lever for releasably supporting the fuse assembly. Also, the barrier plate is somewhat flexible, as heretofore mentioned, so that it readily accommodates itself to variations in dimensions commonly found in cutout casings. This is of importance in that it insures against interference, by the barrier plate, with manual opening and closing of the cutout, as well as the automatic operation of the cutout. Further advantages of the barrier plate are that it acts to retard the rise of expulsion gases from the lower end of the fuse holder into the fuse compartment to cause arcover between the stationary contacts or other conducting parts, and that it minimizes circulation of corrosive and dust laden air through the cutout housing, thereby prolonging the useful life of the cutout.

What I claim as new and desire to secure by Letters Patent of the United States is:

1. In a drop-out cutout, a casing having spaced contacts therein, a door for an open side of the casing, said casing and door forming a compartment open adjacent one end of the casing, a fuse assembly including a fuse holder and spaced terminals therefor arranged for connection with said contacts, a hinge lever pivotally connected with said assembly and hingedly mounted on said casing adjacent said open end of said compartment for supporting said assembly in the compartment, said lever being releasably held against movement relative to said holder by means releasable upon fuse operation, and a barrier plate mounted on said lever adjacent said open end of said compartment and extending transversely

of the compartment into proximity with the walls of said casing and the inner side of said door.

2. In a drop-out cutout, a casing having spaced contacts therein, a door for an open side of the casing, said casing and door forming a compartment open adjacent one end of the casing, a fuse assembly including a fuse holder and spaced terminals therefor arranged for connection with said contacts, a hinge lever pivotally connected with said assembly and hingedly mounted on said casing adjacent said open end of said compartment for supporting said assembly in the compartment, said lever being releasably held against movement relative to said holder by means releasable upon fuse operation, and a relatively thin flexible barrier plate mounted on said hinge lever and extending transversely of said compartment into proximity with the walls of said casing and the inner side of said door, said plate being located intermediate the open end of said compartment and the space occupied by said contacts.

3. In a drop-out cutout, a casing having spaced contacts therein, a door for an open side of said casing, said casing and door forming a compartment open adjacent one end of the casing, a fuse assembly having spaced terminals for connection with said contacts, a hinge lever pivotally connected with said assembly and hingedly mounted on said casing adjacent said open end of said compartment for supporting said assembly in the compartment, said assembly including an expulsion fuse holder arranged to discharge at said open end of the compartment and said lever being releasably held against movement relative to said assembly by means releasable upon operation of a fuse link in said holder, and a barrier plate extending transversely of said compartment adjacent said open end of the compartment, said plate having a portion thereof in at least partially surrounding relation to said holder and formed to provide for relative movement between the holder and said lever.

4. In a drop-out cutout, a casing having spaced upper and lower contacts, a door for an open side of said casing, a fuse holder, said door and fuse holder forming part of an assembly for mounting in said casing, means for connecting a fuse link in said holder between said contacts, means for supporting said assembly with said holder in operative position and said door in closing relation to said open side of the casing, said supporting means including a toggle lever pivotally connected adjacent its upper end to said assembly and hingedly mounted adjacent its lower end on said casing, which said lever is held releasably against movement relative to said assembly by means releasable responsively to rupture of a fuse link in said holder, and a barrier plate extending transversely of said compartment at a point below said lower contact, said plate having a slotted portion fitting relatively closely around said lever and said holder and formed so as to permit relative movement between the lever and holder.

RALPH S. BENNETT.
